UNITED STATES PATENT OFFICE

CHARLES H. KESTENMAN, OF PROVIDENCE, RHODE ISLAND, ASSIGNOR TO KESTENMAN BROS. MFG. CO., OF PROVIDENCE, RHODE ISLAND, A CORPORATION OF RHODE ISLAND

FLEXIBLE METAL CORD AND METHOD OF MAKING SAME

Application filed July 21, 1930. Serial No. 469,517.

This invention relates to improvements in the construction of flexible metal cords, bands and the like for use as necklaces, girdles, wrist-watch straps or bracelets and consists particularly in a hollow cord made from woven or reticulated fabric composed of intermeshed strands of wire.

One object of the invention is to provide a substantially hollow, flexible cord of the type specified formed from a rolled strip of intermeshed wire strands and having a close, smooth joint where the edges of the fabric abut in a seam.

Another object of the invention is to provide a cord of the type specified having the edges of its longitudinal seam so formed as to prevent the wire strands from unraveling or becoming unmeshed.

Another object of the invention is to provide an article of the type specified of more finished and ornamental appearance, with the seam on its side inconspicuous and devoid of projecting ends of the wire liable to scratch the flesh or catch in the garments of the wearer.

Further objects of the improvement are set forth in the following specification which describes a preferred form of construction of the invention, by way of example, as illustrated by the accompanying drawings.

In the drawings:

Fig. 1 is a plan view of a wrist-watch strap or bracelet constructed from a flexible cord embodying the present invention;

Fig. 2 is an enlarged perspective view of a strip or sheet of reticulated wire-mesh fabric from which the cord is constructed;

Fig. 3 is a similar view showing the method of folding the longitudinal edges of the strip to form a selvage therealong;

Fig. 4 is an enlarged perspective view of a relatively short length of the hollow cord formed by rolling the strip of fabric into a tube; and

Fig. 5 is a still further enlarged cross-sectional view of the cord, illustrating a preferred arrangement of the inwardly-folded marginal portions at the seam on its side.

In the present drawings the crosshatching is intended to illustrate the mesh of the wire

strands which are woven, braided or otherwise fabricated in interlocking relationship in any preferred manner as well known to those versed in the art.

The present invention contemplates the use of a strip of fine wire fabric of the nature described, the wire being of gold, silver or platinum, if desired, or in other cases plated with one of these precious metals. In carrying out the invention a relatively narrow strip of such fabric of considerable length is provided, Fig. 2 of the drawings showing only a short section 2 of the strip due to the limitations of the sheet of drawings.

At the first operation in forming the cord the strip 2 is folded along its longitudinal edges substantially on the lines a—a of Fig. 2. Referring to Fig. 3 of the drawings the marginal portions 3 at the sides of the strip are bent inwardly and creased along the folds 4 to cause them to stand at an acute angle to the flat plane of the fabric; the inherent stiffness of the wire providing for a permanent "set" of the folded portions of the fabric. In other cases the marginal portions of the strip may be folded substantially flat against the main strip, although the first described method is preferable for a purpose as later explained.

The folding of the marginal portions of the strip may be performed prior to rolling or forming the fabric into the tubular cord; or the folding and rolling operations may be accomplished at one operation by feeding the strip of fabric through rollers or drawing it through one or more dies.

The strip 2 is rolled or formed into the tubular cord 5, see Fig. 4, by any suitable method, the folded edges 4 being caused to abut in a close seam 6 and the wire fabric being so compressed or constricted as to impart a spring tension thereto tending to resist spreading or separation of the edges of the seam. As the folded edges 4 of the strip are rolled together the inturned portions 3 assume a position as illustrated most clearly in Fig. 5, whereby they act to brace the walls of the tube to resist any tendency to crush or flatten its sides. That is to say, the relatively flat inturned wings 3 of the fabric project

across the interior of the tube in the relation of chords to its arcuate sides, thus forming struts or braces to prevent collapse or crushing of its walls; it being noted that the rough edges of the fabric formed by the ends or points of the wire strands frictionally grip the interior walls of the tube to prevent them from sliding or slipping thereon. Due to this novel and improved method of construction 5 the tubular cord may be composed of thinner and lighter wire mesh, while at the same time being proof against collapsing or flattening of its walls and possessing the necessary attribute of flexibility to adapt it to conform to the shape of the wrist or other contour on which it is worn as a bracelet, necklace, girdle or the like.

The present improved metal cord or band may be embodied in various articles of jewelry and adornment, as before indicated, Fig. 20 1 illustrating one example in the nature of a bracelet for wrist-watches. As shown in this view of the drawings two sections 5 of the cord are doubled to form loops 7 for attachment to the bails on the side of the watch-case, or in other instances to a bracelet ornament, while the ends of the cord are secured to the opposite parts of a clasp 8. Metal slides 10 may be employed to enclose the opposite lengths of the cord to hold them in 25 parallel, adjacent relationship.

Other methods may be used for combining lengths of the cord to form various articles of adornment as practiced in the jewelry and 30 kindred arts, the present invention relating to the structure of the cord itself and not being limited as to its method of use.

It will be observed that the invention provides a particularly simple yet sturdy construction of metal cord for the uses specified, 40 and one having a smoother, more finished and ornamental appearance than similar articles heretofore employed for like purposes.

By folding the longitudinal marginal portions of the fabric inwardly the joint between the abutting edges thereof is made closer and tighter without rough projections or irregular gaps and the strands of wire are prevented from unraveling. With 45 previously used cords the raw edges of the fabric meet in a ragged unsightly seam and the projecting ends of the wire are apt to scratch and injure the flesh of the wearer. Moreover, the present improved structure 55 provides a more durable cord which is proof against unraveling or disintegration of the wire fabric, while the inner bracing or stiffening strips 3 sustain its walls in shape to prevent distortion or collapsing of its sides.

While the invention is herein shown and described as embodied in a preferred form of construction, it is to be understood that I do not limit myself to the exact embodiment disclosed, as various modifications may 60

be made therein without departing from the spirit or scope of the appended claims.

I claim:

1. An article of the type specified comprising a strip of wire mesh fabric having 70 its longitudinal marginal edges folded over and creased and the creased portions of the folds brought together in a close seam to form a round cord.

2. As a new article of manufacture, a metal 75 cord constructed from a strip of reticulated wire fabric folded along its marginal edges and creased in the folds, said strip being rolled into tubular form with the creased portions of the folds abutting in a close seam. 80

3. As a new article of manufacture, a flexible metal cord consisting in a strip of wire mesh fabric having its marginal portions folded inwardly and creased and the strip rolled into a tube with the creased portions 85 of the folds abutting in a close seam and the inwardly directed portions of the fabric extending across the interior of the tube to brace its walls against collapse or compression. 90

4. An improved method of manufacturing flexible metal cords consisting in providing a relatively narrow extended strip of wire mesh fabric, folding the longitudinal marginal portions of the strip inwardly and creasing it at the folds and rolling the strip into a tube with the creased portions thereof compressed into closely abutting relationship. 95

5. An improved method of manufacturing flexible metal cords consisting in providing a relatively narrow strip of wire mesh fabric, folding substantial marginal portions of the strip inwardly to lie at an angle to its face, creasing the folds along the strip, and rolling the strip into a tube to bring the creased portions of the folds into abutting relationship with the inturned marginal portions thereof projected across the interior 100 of the tube in engagement with the interior walls thereof to brace its sides against distortion or collapse. 105

In testimony whereof I hereunto affix my signature.
